UNITED STATES PATENT OFFICE.

GEORGE WILSON GOSS, OF ORLO, TEXAS, ASSIGNOR OF ONE-HALF TO CHARLES M. ACREY, OF CARLSEAD, TERRITORY OF NEW MEXICO.

CALCULATOR.

970,038.

Specification of Letters Patent. Patented Sept. 13, 1910.

Application filed November 18, 1909. Serial No. 528,311.

To all whom it may concern:

Be it known that I, GEORGE WILSON Goss, a citizen of the United States, residing at Orlo, in the county of Reeves and State of Texas, have invented a new and useful Calculator, of which the following is a specification.

This invention has reference to improvements in calculators and is designed to provide a simple and easily manipulated device for the ready calculation of problems of more or less complexity, and especially problems which occur in business transactions.

In accordance with the present invention there is provided a cabinet with passages therethrough by means of which adjustable bands within the cabinet are made visible at the will of the operator to display the desired set of numbers thereon and in conjunction with the cabinet there is provided another band, and an adjustable pointer by means of which various calculations may be rapidly made with a minimum of mental effort.

The invention will be best understood from a consideration of the following detail description taken in connection with the accompanying drawings forming a part of this specification, in which drawings,

Figure 1 is a perspective view of the cabinet with one end broken away to display the internal mechanism. Fig. 2 is a detail view showing the manner of coupling up the winding drums for the number bands. Fig. 3 is a detail section through the guide strip for the indicator bar. Fig. 4 is a detail view showing a manner of differentiating various numbers to be calculated.

Referring to the drawings there is shown a cabinet or case 1 which may be of any suitable material and of any suitable shape, the showing of the drawings being more or less typical or schematic.

The front 2 of the cabinet is formed with a vertical series of longitudinal slots or passages 3 extending for the greater portion of the length of the cabinet.

The passages 3 are terminated at one end at the point more remote from the end of the front portion 2 of the cabinet than at the other end and in the space thus left there is a vertical series of short openings 4 each in line with a respective opening or passage 3.

Within the cabinet are groups of rollers 5, 6, 7, suitably journaled in the ends of the casing and these rollers are coupled together by gear wheels 8 for conjoint motion. The rollers 5 and 7 receive respective ends of a band 9 which is conducted around the roller 6 and this roller 6 is so located that a portion of the band passing therearound is presented close to a respective passage 3 and opening 4, the band being of sufficient width to embrace the distance between one end of the passage 3 and the opposite end of the corresponding opening 4. The journal of each roller 6 is carried through one end of the casing 1 and there receives a manipulating handle 10, so that by turning the handle the several drums carrying a band 9 are caused to rotate in the proper direction to unwind the band from one roller, say the roller 7 and wind it upon the other roller say the roller 5, or by reversing the direction of rotation of the handle 10 the band may be moved in the other direction. Upon the bands are displayed numbers representing predetermined values.

Mounted on the top of the casing at the opposite ends thereof, are vertical spindles 11 each carrying a roller 12 and each spindle also carries a crank 13 by means of which the spindle as well as the roller 12 may be rotated. Fast to the drums or rollers 12 are the respective ends of a narrow band 14 movable by the proper manipulation of the rollers on the top of the casing from end to end of the latter. In front of and closely adjacent to the band 14 is a guide rod 15 fast at the ends to the casing and spaced a short distance from the top thereof. This rod may be of any suitable shape, such for instance, as shown in Fig. 3 where it appears that the rod is slightly flattened on one side, but is otherwise circular in cross section. Applied to this rod is a sleeve 16 having its interior conforming in shape to the cross sectional shape of the rod and this sleeve is capable of being moved along the rod but is prevented from turning thereon because of the bent portion of the rod. From one side of the sleeve 16 there projects a pointer 17 and from the opposite side of the sleeve there projects a bar 18 extending downward along the front 2 of the casing 1 closely adjacent to the said front and traversing the openings or passages 3 therethrough. At one end

of the front 2 of the casing there is secured a pointer 19 in operative relation to the band 14.

Let it be assumed that the calculator is designed for the calculation of interest, then the band 14 will contain time designations such as days, months or years, the uppermost band 9 will display opposite the openings 3 numbers of days in regular order and 10 opposite the opening 4 in line with the top-most opening 3 per cent. designations will be displayed. The next band 9 in order will display large money designations, say thousands, the next lower band will display 15 hundreds, and the still lower band will display units of hundreds, and if desired further bands may be provided with smaller designations. The same bands will display through the passages 3 other predetermined 20 numbers corresponding to the numbers displayed through the openings 4.

By way of example let it be assumed that it is desired to ascertain the interest on \$1,101.00 at 10 per cent. for fifty-five days.

25 Then the uppermost band is moved to display the ten per cent. designation through the corresponding opening 4 and day designations will appear through the corresponding passage 3. The second band is moved 30 to display the number 1,000 through the corresponding opening 4, the third band is moved to display the number 100 through the corresponding opening in passage 4 and the next band is moved to display the number 1 through the corresponding opening 4. Under the conditions assumed all the rollers are moved to an extent that the designations displayed through the passages 3 will correspond to ten per cent. on the sums displayed 35 through the passages 4. On now moving the slide 16 to a point corresponding to the number of days for which it is desirable to find the interest, it is only then necessary to add the various sums found in line with 40 the slides on the various bands 9 displayed through the passages 3. This sum will give the interest at ten per cent. on \$1,101.00 for fifty five days. Let it be assumed that a similar problem should be proposed except 45 that it be desirable to ascertain the interest for a period of time between two dates, then the band 14 is employed, the first of the dates being brought into coincidence with the pointer 19 and the pointer 17 is brought 50 opposite the second of the two dates. Under these circumstances the bar 18 will show 55

in the passages 3 the interest on the sums displayed at the passages 4. By properly arranging other series of numbers upon the bands 9 and 14 other problems than the ascertaining of interest may be as readily solved.

The bands 9 may be of considerable length and contain thereon figure designations for various purposes. In order that 60 these may be readily observed by the operator each band 9 may have the figure designations for various purposes in differently colored zones such for instance as illustrated in Fig. 4, where the zones are schematically 65 displayed at 20, 21, 22, 23.

What is claimed is:—

1. A calculator comprising a suitable casing having a series of aligned and respectively long and short passages for the display of circumscribed portions of the contents of the casing, bands within the casing each movable into visible relation to respective aligned passages, a band on top the casing adjustable in the direction of its length, 80 a rod along the top of the casing adjacent to the band thereon, a fixed pointer on the casing in operative relation to the band, and a sleeve on and movable along the rod and provided with a pointer on one side in operative relation to the band on the casing and a rod on the opposite side movable over all the passages in the casing simultaneously, the sleeve and rod being relatively shaped to prevent turning of the sleeve on 85 the rod.

2. A calculator comprising a suitable casing having passages therethrough for the display of circumscribed portions of the contents of the casing, bands within the 90 casing movable into visible relation to the passages therethrough and each provided with distinctive zones with series of numbers thereon differentiated by the distinctive zones, all the zones on each band being movable into visible relation to a respective passage through the casing, and an indicator member movable lengthwise of all the 95 passages simultaneously.

In testimony that I claim the foregoing 100 as my own, I have hereto affixed my signature in the presence of two witnesses.

GEORGE WILSON GOSS.
